FOAMITE FIRE-EXTINGUISHING SYSTEM

Claude H. Trotter and Arthur W. Sweeney, Phillips, Tex., assignors to Phillips Petroleum Company, a corporation of Delaware.

Application November 14, 1949, Serial No. 127,172

6 Claims. (Cl. 169—4)

1

This invention relates to apparatus for extinguishing fires in tanks in which inflammable liquids are stored. In one aspect, it relates to apparatus for extinguishing fires in the open top tanks having floating roofs.

In storage tanks in which inflammable liquids are stored fires occasionally occur due to ignition of an inflammable mixture of vapors of the liquid stored with air. The ignition of such mixtures may be occasioned by lightning or sparks caused by contact of certain metals with metal parts of the tank. Tanks having fixed, rigid roofs possess relatively large vapor spaces, that is, any portion of the tank not filled with liquid will be filled with vapors of the liquid in case the liquid stored is volatile. When such a liquid is pumped from the tank and if air displaces the liquid, an explosive mixture may then exist within the vapor space of the tank. In order to avoid such dangerous conditions, the floating roof was devised for use in tanks in which are to be stored such inflammable liquids as gasoline. The floating roof has been used in the oil industry for many years.

Fires in tanks are also caused as a result of the storage of liquids containing hydrogen sulfide. Hydrogen sulfide in the oil reacts with the iron or iron rust on the tank walls to form an iron sulfide. When the tank roof descends this iron sulfide dries and becomes pyrophoric. Ignition is spontaneous and a tank fire results when inflammable vapors are present.

Floating roofs are so constructed that upon filling or emptying a tank of its contents, the roof rises or descends. Such a roof cannot be made to form a vapor-tight joint with the walls of the tank and at the same time be movable due to irregularities in the walls of the tank. In order to make the floating roof cover the surface of the liquid as nearly as possible, an expansible joint has been devised to take up irregularities in the walls of the tank as a roof ascends or descends. Even such an expansible joint does not contact the walls of the tank in a truly vapor-tight manner, and vapor leakage outward or air leakage inward, or both may occur. It is at such points on the roof of the tank that fire ordinarily begins. Since the entire roof of the tank, with the exception of the circular, annular, expansible joint of relatively small width disposed between the periphery of the rigid roof and the walls of the tank, is constructed of a metal, the point at which fire ordinarily begins is in this annular expansible joint.

An object of my invention is to devise apparatus

for fighting fires around the periphery of the floating roof of a floating roof tank.

Another object of my invention is to provide an apparatus for the injection of fire-fighting foam into the vapor space of an expansible joint between the floating roof and the walls of a floating roof tank.

Still another object of my invention is to provide an apparatus for the fighting of fires around the periphery of the floating roof tank in which foam fire-fighting material can be quickly and effectively distributed over the surface of the liquid.

Still other objects and advantages of my invention will be realized upon reading the following disclosure which, taken with the attached drawings, forms a part of this specification.

Figure 1 of the drawing is an elevational view, partly in section, of an open top storage tank having a floating roof and equipped with the fire-fighting apparatus of my invention. Figure 2 is a plan view, in part, of such a floating roof tank. Figure 3 is a plan view on an enlarged scale of a portion of the apparatus of my invention. Figure 4 is an elevational view of the apparatus of Figure 3. Figure 5 is a view, partly in section and partly in elevation and on an enlarged scale of a portion of the floating roof embodying my invention.

Referring now to the drawing and specifically to Figure 1, a tank 11 is provided with several inlet and outlet pipe connections, 12, 13 and 14. Such pipe connections are more or less conventional apparatus with tanks. Tanks which are intended for use in the storage of petroleum or petroleum products frequently contain some water and it is customary that one of the pipe connections, as for example, connection 13, be provided for the removal of the water from beneath the oil. Connection 12 is for inlet and outlet of the product stored or even separate inlet and outlet connections may be provided. Pipe connection 14 passes through the walls of the tank and is connected to a pipe 15 inside the tank, which pipe is ordinarily some type of flexible conduit and this conduit leads to the floating roof and is used for removal of water accumulating on the floating roof.

The floating roof assembly 16 is of conventional construction and consists of an air chamber 19 bounded by sheet steel. The bottom section of the air chamber 19 is identified by reference numeral 18, and this metal section 18 and the horizontally disposed sheet metal 17 form the portions of the floating roof which contact the

larger portion of the surface of the liquid in the tank. Since the floating roof of course possesses considerable weight, it displaces some liquid, and the liquid rises above the bottom of the air chamber 19 as may be seen between the air chamber wall 24 and the wall of the tank 11. The flexible sealing means disposed between the periphery of the floating roof and the wall of the tank consists of the slideable shoe members 20 supported by the support members 23, springs 22 and braces 22a. The top of the shoes 20 are connected with the outer and upper edge of the air chamber 19 with a flexible material 21, such as canvas. This flexible material 21 is intended to flex and yet maintain a tight seal between the top of the shoe members 20 and the outer edge of the floating roof as the roof ascends or descends within the tank.

When the flexible sealing material 21 is new and undamaged, the seal between vapors under the material 21 and the atmosphere is ordinarily effective. With the passage of time, however, such sealing material sometimes becomes damaged and torn or may become rotten or even hard and brittle. Under such conditions, when this material is of an inflammable nature an additional hazard exists. Also, this material is easily ruptured and when broken or torn in any manner, vapors from the liquid being stored have an opportunity to become mixed with air, thereby forming an explosive mixture. This explosive mixture is then present in the space above the surface of the liquid 40 and below the sealing member 21 and between the side wall 24 of the air chamber 19 and the shoes 20. Thus this portion of the tank is vulnerable to explosion and fire.

My invention comprises an apparatus which is adapted for the rapid introduction of the fire fighting foam into this vapor space between the flexible material 21, the surface of the liquid 40, the shoes 20 and the side of the roof 24.

Fire-fighting foam from a source of supply 39, outside of the tank, is passed through a pipe 41 into a pipe connection 32 in the wall of the tank at a point near its base. The foam then passes through a flexible conduit 33 to a distributing head 34 which is disposed on the floating roof at a point near the center. This distributing head 34 is shown in detail in Figures 3 and 4 and consists mainly of a vessel 42 having a number of pipe connections 43. To these connections 43 are fastened some conduits 35 and 36. These conduits 35 and 36 are for the purpose of transmitting the fire-fighting foam from the vessel 42 radially to several points within the above-mentioned vapor space. As many pipe connections 43 may be provided in the vessel 42 as desired. In general, for tanks of greater diameter, more of these pipe connections 43 and conduits 35 and 36 are provided. The conduits 35 and the upper portions of the conduits 36 pass through the air chamber 19 as pipes 37. To the ends of the pipes 37 are attached some T's 38. The T's 38 are so positioned that foam passing through pipe 37 will enter the vapor space in a direction normal to the axis of the pipes 37. In a tank such as illustrated in Figure 1 when eight radial conduits 35 and 36 are used and foam is transmitted in both directions from the ends of each conduit, the foam spreads over the entire surface 40 of the liquid in the vapor space in a very short time. One of the important points in fighting a fire, such as an oil fire is to extinguish the fire before the metal parts of the tank have had an oppor-

tunity to become heated. Since the oil may be rekindled from the heated walls or other hot objects, the utility of my distributing apparatus is evident. In Figures 1 and 2, two of the conduits

5 36 are positioned lower and closer to the central portion of the roof 17 than are the conduits 35. Conduits 36 are positioned near the surface of the roof to accommodate the ladder track. These two lower conduits 36 are provided with weep 10 holes through which foam may be drained from the conduits 36. Such drained material may then be washed with water and removed from the roof through the flexible pipe 15 and passed through pipe 14 for such disposal as desired. Conduit 15 also serves for disposal of rain water. Valved pipes 41a and 34a are provided for drainage of foam and flushing purposes.

On the underside of the roof are some depending 20 members 31 which are intended to act as posts or supports for supporting the floating roof in times when all, or substantially all, of the liquid is pumped from the tank.

In the operation of the apparatus of my invention when a fire occurs around the periphery 25 of the floating roof, it is merely necessary to pump fire-fighting foam from its source 39 through pipe 41, connection 32, and flexible conduit 33, into the distributing head 34. From this head the foam radiates through conduits 35 and 30 36 and is very quickly distributed through the several T members 38. As soon as the entire surface 40 of the liquid is covered with foam, the source of the inflammable vapors is sealed off.

Materials of construction for this foam distributing 35 system may be selected from among those commercially available which are suitable for handling such materials. In general, ordinary 40 steel pipes and sheets are satisfactory. As many conduits 35, 36, and distribution T's 38 may be used, as are warranted according to the size of the tank. Any type or form of distributing head 34 may be used providing the head is adapted to rapid distribution and flow of fire-fighting foam. Any type of flexible pipe may be used for the pipe 45 33 providing the flexibility is such that all joints and portions of pipe are tight and fluid proof and adapted to deliver foam to the distributing head regardless of the position of the roof.

The above-described foam distributing apparatus 50 is given for illustrative purposes and should not be regarded as limiting the invention, the scope of which is set forth in the following claims.

Having described our invention, we claim:

1. Apparatus for use in extinguishing fire in 55 storage tanks in which inflammable liquids are stored and having a floating roof, slideable shoes attached to the periphery of said floating roof with a flexible material to form a seal between said floating roof and the vertical wall of the tank and affording a closed vapor space bounded by the surface of the inflammable liquid, the slideable shoes, said flexible material, and the periphery of said floating roof, comprising a first pipe 60 extending through the wall of the tank, a conduit in said tank having one end attached to said first pipe and the other end attached to one end of a second pipe extending through said floating roof, said second pipe extending radially above said roof and terminating at a point within said vapor space and means to supply fire extinguishing foam to said first pipe.

2. Apparatus for extinguishing fire in an oil 65 storage tank having a floating roof, slideable metal shoes attached to the periphery of said floating roof with a flexible material to form a seal be-

tween said floating roof and the vertical wall of the tank and affording a closed vapor space bounded by the surface of oil, the slideable shoes, the flexible material and the periphery of said floating roof, comprising a first pipe extending through the wall near the base of the tank, a conduit in said tank having one end attached to said first pipe and the other end attached to one end of a distributing head extending through said roof, one end of each of a plurality of distributor pipes connected with said distributing head, said plurality of pipes extending radially toward the wall of the tank and terminating in said vapor space, and means to supply fire extinguishing foam to said first pipe.

3. In the apparatus of claim 2 a pipe T attached to the end of each pipe of said plurality of pipes in said vapor space for distributing fire-fighting foam over the surface of said oil exposed to said vapor space.

4. An apparatus comprising, in combination, an open top tank for storing inflammable liquid, a floatable roof for covering the surface of said liquid, slideable metal shoes attached to the periphery of said floating roof and joined thereto by a flexible material to form a seal between said floating roof and the vertical wall of said tank and forming a closed vapor space bounded by the surface of said inflammable liquid, the slideable shoes, said flexible material and the periphery of said floatable roof, a first pipe extending through the wall of said tank at a point near its base, a second pipe extending through said floatable roof and attached to a distributing head mounted on said roof, a conduit connecting said first and second pipes, a plurality of pipes extending radially from said distributing head toward the walls of said tank, a pipe T attached to the end of each of said plurality of pipes and said T's terminating in said vapor space and so disposed that the axes of the side inlets of said T's are coincident with the axes of said radially disposed pipes at the point of contact with said T's, and means for supplying fire extinguishing foam to said first pipe.

5. Apparatus for use in extinguishing fire in storage tanks in which inflammable liquids are stored and having a floating roof, slideable shoes attached to the periphery of said floating roof with a flexible material to form a seal between said floating roof and the vertical wall of the tank and affording a closed vapor space bounded by the surface of the inflammable liquid, the slideable shoes, said flexible material and the periphery of said floating roof comprising in combination, a source of fire fighting foam, a first conduit extending from said source of foam through the wall of the tank, a conduit means in said tank in fluid communication from said first conduit to a point above the surface of said floating roof, a second conduit in fluid communication with said point and extending therefrom to a point within said vapor space.

6. In combination with a tank having an open top for storing inflammable liquid, a roof adapted to float on the surface of said liquid and disposed in said tank to close the major portion of said open top, a flexible and expansible vapor sealing member secured to the periphery of said roof and biased into vapor sealing relation with the walls of said tank whereby a closed vapor space is formed above said liquid between said sealing member and said roof, a supply of fire extinguishing foam under pressure and a conduit secured to said roof connecting said supply and said vapor space.
